(57) **CLAIM**

The ornamental design for a fish finder picture frame, as is shown and described.

DESCRIPTION

FIG. 1 is an isometric view of a fish finder picture frame showing my new design;

FIG. 2 is a top side view thereof;

FIG. 3 is a bottom side view thereof;

FIG. 4 is a left side view thereof;

FIG. 5 is a right side view thereof;

FIG. 6 is a front side view thereof; and

FIG. 7 is a rear side view thereof.

The broken lines within the figures are used for illustrating environmental structure and form no part of the claimed design.

1 Claim, 7 Drawing Sheets
